CLOTHINGS FOR FLATS OF CARDING
MACHINES

Auguste Mathieu Alfred Freitag, deceased, late of Rue
Bellevue 18, Lambermont, Belgium, by Antoinette
Maria Cornelie Lemahieu, executrix, Lambermont,
Belgium

Filed June 18, 1959, Ser. No. 821,159
1 Claim. (Cl. 19—114)

The present invention relates to clothings for flats of carding machines.

For years the so called "all-steel clothing" has been developed with considerable success for the cylinders and taker-in rollers of carding engines which clothing consists of wire members having rigid hardened steel teeth directed outwards and these have proved to be comparatively satisfactory.

In addition the so-called "semi-rigid" clothing has been in use for years which like the other coverings are wound on the drums and taker ins in the form of bands. The semi-rigid clothing consists of a multi-layered covering in which instead of round wire teeth narrow steel members with obliquely chamfered ends are inserted. The rigid ends are in contrast with the rigid all steel clothing located resiliently in the base material the outer layers of which are coarser or of wider mesh than the inner layers (see Swiss patent specification 211,092).

Because of the disadvantages the use of completely resilient clothing for flats the chief of which is the necessity for frequently stripping out the high content of good fibres from the flat clothing, attempt has also been made to provide the flat with a rigid so called all-steel covering. This however fails in practice in that the flats because of the great weight of the all-steel covering are subject to distortion and therefore the distance of the drum clothing teeth from the flat clothing teeth over the whole width of the carder necessary for a satisfactory working of the carder cannot be maintained.

For flat cards it is a general rule that the flat clothing must have a greater density of teeth by at least 10 English clothing counts numbers than the drum clothing. For this reason the flat clothing of flat carders has hitherto an English clothing count number of 90 to 140. Such a high count number can only be manufactured with clothing with resilient teeth of very thin wire whilst the so called "semi-rigid" clothings with sufficiently stiff flat wire teeth can be made only with considerably lower clothing count numbers and therefore do not come into consideration for the covering of flats quite apart from the fact that because of the flexible mounting of the rigid teeth and the small distance between the flat and the drum the drum covering is easily damaged.

The object of the present invention is a clothing for the flats of a card comprising a band of fabric of several layers characterised in that the band comprises several compressed layers of rigid fabric forming a base and serving for the fixing of teeth formed of known U-shaped members and comprising flat metal wires the direction of the middle portions of which is parallel to that of the band and the legs of which form the teeth having the ends chamfered at an acute angle and being embedded so as not to bend nor curve.

Another feature is that the U-shaped members are disposed in rows and in each of the rows the middle portions located at the back of the band are substantially in contact.

Thus the middle bridge portions of the U-members lying side by side with metal to metal contact may be staggered relatively to one another in one direction in

such a way that the right angled legs forming the side boundaries of the middle bridge portion are staggered as seen from underneath.

In the drawings:

5 FIGURE 1 is an end view of a conventional flat having a resilient card clothing,

FIGURE 2 is a view similar to FIGURE 1 of another form of conventional flat,

10 FIGURE 3 is a view similar to FIGURES 1 and 2 illustrating the flat of the present invention,

FIGURE 4 is an enlarged fragmentary bottom plan view of the base portion of the device illustrated in FIGURE 3,

15 FIGURE 5 is a further enlarged fragmentary perspective view of the base shown in FIGURE 4,

FIGURE 6 is an enlarged cross sectional view of a tooth forming a part of the invention,

20 FIGURES 7 to 10, inclusive, are views similar to FIGURE 6 but illustrating various other cross sectional shapes the teeth may assume,

FIGURE 11 is an enlarged perspective view of a tooth construction in accordance with the invention,

25 FIGURE 12 is a greatly enlarged fragmentary perspective view of a portion of the tooth illustrated in FIGURE 11, and

FIGURE 13 is a view similar to FIGURE 12 but illustrating another but unpreferred form the invention may assume.

30 In FIGURE 1 there is shown an end view of the usual flat on the base plate 3 of which is mounted the base 1 of a resilient card clothing 2, by means of clamps 4 or the like.

In FIGURE 2 there is shown the same view of a flat with all-steel clothing 5 which however—as mentioned above—because of the bending caused by its great weight has not progressed beyond the experimental stage and has not been able to find any acceptance in practice.

35 FIGURE 3 shows the same end view of a flat in accordance with the new idea with a clothing (according to the invention) in the base 8 of which formed of a plurality of textile layers the U-shaped teeth 6 of flat steel wire having points 7 are inserted with metal contact of their bight portions 10.

40 FIGURE 4 shows the back of the base 8 of a clothing for the flat in accordance with the invention and

45 FIGURE 5 shows on a considerably enlarged scale a perspective view partly in section of the base consisting of textile layers 11 with a rubber covering layer 12 in which three U-shaped teeth 9 lying against one another 50 side by side with metal contact of their bight portions 10 are mounted. The teeth are provided with tapered and pointed outer end portions.

55 FIGURES 6—10 are, respectively, transverse cross sections of a flat wire rounded at its edges, of a wire of oval or double convex section, an ovoid section wire, 55 a wire of torpedo section, and a substantially triangular section wire.

60 FIGURE 11 is a perspective view of a U-shaped tooth element formed from a wire having the cross section of FIGURE 10.

FIGURE 12 is an enlarged fragmentary view of one of the tooth points of FIGURE 11.

65 FIGURE 13 is a view similar to FIGURE 12 showing a tooth point formed from a wire of rectangular cross section.

70 With the resilient clothing with round wire teeth hitherto used for the flats in carding machines numbers of teeth are bent back to a considerable extent so that they are not in action and do not participate at all in the carding process. In reality only about half or less than half of the teeth actually present participate in the carding process and this number during the whole

working process is subjected to considerable fluctuations according to the amount of impurities to be separated out of the fibre fleece located on the drum.

If the needles of the flat clothing are rigid, however, as for example, with the all steel clothing or semi-rigid as in the clothing according to the invention, then a more uniform cleaning and combing is ensured because continuously the same number, namely an exactly predetermined number of teeth participate in the carding process. Thus the number of the teeth of a given wire count numbers actually working is quite substantially greater than that of the resilient clothing in general use up to the present time employing a considerably higher number under certain circumstances as high as double the wire count number.

As an example the clothing count number for a flat according to the invention may be for instance 55 i.e. 256 teeth per square inch for a count number in the drum clothing of 500-550 teeth per square inch.

The main advantages of such a card clothing for flats is that:

- (1) During carding a tooth retains its power to regulate the fibres; its action remains consistently efficient and consequently the carding is regular; the card sliver acquires a desirable regularity.
- (2) The ends of the teeth do not approach the clothing with which they work in opposition. Also:
  - (a) Regular carding and therefore a card sliver of desirable characteristics is produced.
  - (b) It is possible to adjust the space between the 30 clothings to a small distance with consequent optimum disentangling of the fibres.

In carrying out the invention the fabric base may be a homogeneous laminated fabric made up of identical plies i.e. formed of plies of a woven cotton fabric such as white cloth having the same number of warps and the same number of wefts in each ply.

Alternatively the fabric may be a mixture of layers of cotton and linen or hemp.

For instance, a fabric that has proved to be very 40 satisfactory is one formed of 5 plies of cotton and two interposed plies of linen.

As a cohering agent, use may be made of synthetic rubber or other synthetic or plastic product. Such a mixture consists of a superimposition of the rubber covering layers as is employed for example in the manufacture of pneumatic tires for motor vehicles obtained by permanently adhering the layers by impregnation with a synthetic rubber.

As an adhesive a gelatine adhesive is preferably employed such as that usually used under the name of "Cement" in connection with card clothing.

Such a fabric has the property of resisting the sun's rays or the heat and light of equatorial countries.

It may also be employed without danger of destruction with materials having an oil or chemical base capable of attacking natural rubber.

According to a further feature the teeth are formed of flat steel wire having a section with at least one rounded or acute side.

The sections of the wire may be for example:

- (a) A flat wire rounded at both ends (FIG. 6)
- (b) A wire of oval or double convex section (FIG. 7)
- (c) A wire of ovoid section (FIG. 8)
- (d) A wire of torpedo section (FIG. 9)
- (e) A wire of substantially triangular section 10 (FIG. 10).

Such wires have the property of presenting a better cutting edge giving better opening of the fibres and presenting a sharper profile to the material to be carded.

The advantage of the section of FIGURE 10 is that the bevelled portion 13 is terminated by a single edge 14 (FIGS. 11 and 12) whilst in the case of a rectangular section the extremity comprises two right-angles 15 (FIG. 13).

This application is a continuation-in-part of application Serial No. 459,797, filed October 1, 1954, now abandoned.

What is claimed is:

A card clothing for the flats of carding engines comprising a flat rectangular base formed of a plurality of layers of relatively strong cloth, and straight pointed teeth extending perpendicularly with respect to the outer surface of said base, each pair of teeth comprising a U-shaped wire having its bight portion extending parallel to the longitudinal axis of and abutting the rear face of said clothing and having its leg portions extending through said clothing, said U-shaped wires arranged in rows at an inclination to the longitudinal axis of the clothing, said bight portions being in abutting relation to one another, said U-shaped wire being of generally isosceles triangular cross section with slightly rounded fiber protecting apices and with the smallest angle lying between the equal sides, and the ends of said legs being cut at a bias so as to provide relatively sharp points at the smallest angle apex, whereby optimal strength and point sharpness consistent with low mass of said wire are obtained.
